UNITED STATES PATENT OFFICE.

WALTER C. TAYLOR, OF ST. LOUIS, MISSOURI.

DESIGN FOR A BOTTLE.

SPECIFICATION forming part of Design No. 31,127, dated July 4, 1899.

Application filed May 25, 1899. Serial No. 718,307. Term of patent 14 years.

To all whom it may concern:

Be it known that I, WALTER C. TAYLOR, a citizen of the United States, residing in St. Louis, State of Missouri, have invented and 5 produced a new and useful Design for a Bottle, of which the following is a specification, reference being had to the accompanying drawings, forming a part hereof, in which—

Figure 1 is a front perspective view, and 10 Fig. 2 a rear perspective view, of the bottle embodying the design.

As shown in the drawings, the leading or material feature of my design consists in a bottle with the body portion having the shape 15 of a bell, with the back portion thereof flat. The bottle has the flat back face *a*, and extending in a regular circular curve therefrom

is the front body portion *d*, having the shape of a bell. Above the body portion is the neck *c* and mouth *d*. 20

The design provides a bottle which can lie upon a flat surface and yet presents the appearance of a bell.

What I claim, and desire to secure by Letters Patent, is—

The design for a bottle herein shown and described.

In testimony whereof I, the said WALTER C. TAYLOR, have hereunto set my hand.

WALTER C. TAYLOR.

Witnesses:

RUDOLF A. MEYER,
JAMES C. BROOKS.
